TOILET COVER AND SEAT LIFT

George Hompesch, Irvington, N. J.

Application August 10, 1938, Serial No. 224,057

7 Claims. (Cl. 4—251)

This invention relates to toilet cover and seat lifts and, more particularly, to such a device in which the cover of a toilet may be lifted independently of the seat by a person without the use of his hands.

In the past such devices have operated to raise both the seat and cover of a toilet at one and the same time or if the cover was to be raised independently of the seat the same would have to be raised by means of a person's hands.

An object of my invention is to provide a device by which a person may raise the cover and the seat of a toilet by means of his foot but which device will raise the cover independently of the seat.

Another object of my invention is to provide a device of this character which may be easily and neatly attached to the cover and seat of a toilet.

A further object of this invention is to provide an apparatus for raising or lowering the cover and seat of a toilet by means of foot pressure in which the operator will not have to touch either the cover or seat of a toilet with his hands in order to raise the cover independently of the seat.

Other objects will appear or will be obvious from a consideration of the detailed description which follows taken in conjunction with the accompanying drawing.

The apparatus of the present invention consists of a foot lever pivoted near the base of a toilet said foot lever being pivotally connected to one end of a main lever which is pivotally mounted intermediate its length on the toilet seat at one side and near the rear of said seat. The opposite end of the main link is pivotally connected to one end of a lever the opposite end of which is pivotally mounted on the toilet cover, said mounting being slightly forward of the mounting on the toilet seat. The toilet seat and cover are hinged to the bowl of the toilet in the usual manner.

It will be understood, however, that the invention is not restricted to the exact disclosure, but is susceptible to such changes and modification which are within the scope and purview of the appended claims.

Referring to the accompanying drawing—

Figure 1 is a side view showing the apparatus of the present invention mounted on a toilet, the seat and cover being in closed position.

Figure 2 is a view similar to Figure 1 showing in full lines the position of the apparatus when the cover is opened and showing in dot and dash

lines the position of the device when the seat and cover are both opened.

Figure 3 is a perspective view of the device mounted on a toilet showing both the seat and cover in a closed position.

The apparatus of the present invention consists of a foot lever 10 on one end of which is fastened a foot pedal 11.

The said foot lever 10 is pivotally mounted in a fastening 12 which fastening may be secured to the side of the toilet bowl 13, as shown in the drawing, or may be mounted on the floor. At a point near the foot pedal 11 is a foot pedal control device 14 which is adapted to be connected with the foot pedal lever 10 preferably at a point 15 near the foot pedal 11. This control device may be in the form of an air or hydraulic controlled plunger or may consist of a spring, the function of said device being to retard the closing of the toilet seat and cover. This device may also be 20 attached to the side of the toilet bowl 13 or to the floor.

The opposite end of the foot pedal lever 10, to which the foot pedal 11 is attached, is pivotally connected at 15 to one end of the connecting rod 25 16. The other end of the connecting rod 16 is pivotally mounted on a lever 17. At a point intermediate its length, the lever 17 is pivotally mounted at 18 to a fastening 19 which fastening is secured preferably to the under side of toilet 30 seat 20 at a point closely adjacent the rear and to the side of said toilet seat.

The lever 17 is so formed that it has an arm 21 formed integrally therewith which arm is offset so that the end 22 to which the connecting 35 rod 16 is pivotally mounted is slightly forward of the pivot point 18. The opposite end 23 of the lever 17 extends slightly above the toilet cover 24 and is pivotally connected at 25 to a cover lever 26. The cover lever 26 is pivotally mounted at 40 21 on a fastening 28 which is secured preferably to the underside of the toilet cover 24 at a point slightly forward of the pivot point 18.

The toilet seat 20 and the toilet cover 24 are hinged to the toilet bowl 13 in the usual manner 45 as shown at 29. The usual water tank for a toilet is shown at 30.

When it is desired to use the apparatus of the present invention the operator presses his foot downwardly on the foot pedal 11. This downward pressure on the foot pedal 11 causes the foot lever 10 to pivot in the fastening 12 which raises the opposite end of the said foot lever. This action moves the connecting rod 16 upwardly and forwardly through its pivotal con- 55

nexion with the foot lever 10 at 15 and its pivotal connection with offset arm 21 of the lever 17 at 22. This downward pressure on the foot pedal 11 causes the lever 17 to pivot on the fastening 19 at 18 due to the fact that the arm 21 is offset forwardly of the pivot point 18. The end 23 of the lever 17 is swung backwardly toward the water tank 30 of the toilet.

In moving backwardly and downwardly the 10 lever 17 moves the arm 26 backwardly which initiates the upward movement of the toilet cover 24 which pivots on the hinge 29, due to the fact that the pivot point 27 between the lever 26 and fastening 28 is forward of the pivot point 18 between 15 the fastening 19 and lever 17.

The pivot point 25 moves in an arc of which the pivot 18 on the fastening 17 is the center.

The cover lever 26, since it is pivotally connected to the lever 17 at 25 follows the pivot point 20 25 as it moves through said arc, the lever 26 pivoting about the pivot point 25 on the lever 17 and the pivot 27 fastened on the toilet cover 24. This action swings the toilet cover open, the apparatus assuming the position shown in full lines 25 in Figure 2, the cover 24 coming to rest against the water tank 30.

When it is desired to raise the toilet seat, further downward pressure is exerted by the operator on the foot pedal 11. Since the toilet cover 30 24 is fully opened and resting against the back of the water tank 30 no further movement can be imparted thereto, therefore, as the foot lever 10 moves upwardly further, the connecting rod 16 imparts an upward movement to the lever 17 through its pivotal connection at 22 with the arm 21. The arm 17 then pivots on the pivot connection 25 between the lever 17 and the lever 26 which raises the toilet seat.

As the toilet seat raises, the lever 26 swings 40 40 backwardly on the pivot 27 of the toilet cover fastening 28 until the toilet seat comes to rest in its fully opened position against the toilet cover 24 which is at rest against the water tank 30.

The position of the apparatus, when the toilet seat and the toilet cover are fully opened, is shown in dot and dash lines in Figure 2.

When it is desired to close the toilet seat 20, the operator initiates the downward movement of the same by pressing his foot momentarily on the part of the foot pedal 11 nearest the fastening 12 and then removing his foot from the same. This in turn will impart a downward movement to the connecting rod 16 which will draw the arm 21 of the lever 17 downwardly about the pivot point 18. The end 23 of the lever 17 is given a slight upward movement which imparts a forward movement to the seat 20 through the action of the said end 23 on the cover lever 26 which is pivotally mounted on the cover 24. The seat 20 50 55 will move downwardly independently of the cover 24 due to the greater weight of the seat 20. The seat 20 moves downwardly in an arc of which the hinge 29 is the center, the cover lever 26 moving forwardly in an arc of which the pivot point 27 is the center.

The foot pedal control device 14 which, as shown in the drawing, consists of a pull-spring, will retard the closing movement of the seat 20 since the end of the foot pedal lever 10 to which the foot pedal is attached moves upwardly against the tension of the spring as the toilet seat is closed.

After the toilet seat 20 has been closed leaving the toilet cover 24 remaining in an open position, 70 75 and it is desired to close said cover, or should

the toilet cover only have been raised and it is desired to close the same, the operator initiates the downward movement of the same by pressing his foot momentarily on the part of the foot pedal 11 nearest the fastening 12 and then removing his foot from the same. This action will impart a downward movement to the opposite end of the foot pedal lever 10 which will draw the connecting rod 16 downwardly imparting a downward movement about pivot 18 to the arm 21 of 10 the lever 17 on the toilet seat fastening 19. This will cause the end 23 of the lever 17 to move in an arc of which the pivot 18 is the center. Such a movement will, in turn, impart a forward movement to the toilet cover 24 through the pivotal connection 25 between the lever 17 and the lever 26 and the pivotal connection 27 between the lever 26 and the toilet cover fastening 28.

The foot pedal control device 14 will act to retard the closing of the toilet cover in the same 20 manner as it retards the closing of the toilet seat as previously described.

It may be readily understood that the present invention may be adapted in different ways to accomplish the purposes set forth and it is not 25 my intention to limit the invention to the exact details of construction shown and described but rather to cover all equivalent structures as defined by the scope of the following claims.

I claim:

1. In combination with a toilet having a seat and cover hingedly mounted thereon, means for limiting the upward movement of said seat and cover, a lever extending upwardly pivotally mounted intermediate its length on said toilet seat one end of said lever extending above said toilet seat when the same is in its closed position, a lever having one end pivotally connected to said toilet cover forward of the pivot point of said first-mentioned lever on the toilet seat and having the other end pivotally connected to the upwardly extended lever, a foot lever pivotally mounted at the base of said toilet, and a rod pivotally connected to one end of said foot lever and extending upwardly the other end of said rod being connected to said upwardly extending lever, the connection between said upwardly extending lever and said rod being forward of the pivotal connection between said rod and the foot lever.

2. In combination with a toilet having a seat and cover hingedly mounted thereon, means for limiting the upward movement of said seat and cover, a fastening mounted on said toilet seat, a lever extending upwardly pivotally mounted intermediate its length on said fastening one end of said lever extending above said toilet seat when in its closed position, the other end of said lever being offset forwardly, a fastening mounted on said toilet cover forward of said fastening on the toilet seat, a lever having one end pivotally connected to said fastening on the toilet cover and the other end pivotally connected to said upwardly extending lever, a foot lever pivotally mounted at the base of said toilet, and a rod pivotally connected to one end of said foot lever and extending upwardly the other end of said rod being pivotally connected to said offset end of said upwardly extending lever, the connection between said offset portion of said upwardly extending lever and said rod being forward of the pivotal connection between said rod and foot lever.

3. In combination with a toilet having a seat and cover hingedly mounted thereon, means for limiting the upward movement of said seat and cover, a fastening mounted on said toilet seat,

5 a lever extending upwardly pivotally mounted intermediate its length on said fastening one end of said lever extending above said toilet seat when in its closed position, a fastening mounted 5
 10 on said toilet cover forward of said fastening on the toilet seat, a lever having one end pivotally connected to said fastening on the toilet cover and the other end pivotally connected to said upwardly extending lever, a foot lever pivotally mounted at the base of said toilet, and a rod pivotally 10
 15 connected to one end of said foot lever and extending upwardly the other end of said rod being pivotally connected to said upwardly extending lever, the connection between said upwardly extending lever and said rod being forward of the pivotal connection between said rod and the foot lever.

4. In combination with a toilet having a seat and cover hingedly mounted thereon, means for 20
 20 limiting the upward movement of said seat and cover, a fastening mounted on said toilet seat, a lever extending upwardly pivotally mounted intermediate its length on said fastening one end of said lever extending above said toilet seat 25
 25 when in its closed position, the other end of said lever being offset forwardly, a fastening mounted on said toilet cover forward of said fastening on the toilet seat, a lever having one end pivotally connected to said fastening on the toilet cover 30
 30 and the other end pivotally connected to said upwardly extending lever, a foot lever pivotally mounted at the base of said toilet, a rod pivotally connected to one end of said foot lever and extending upwardly the other end of said rod being pivotally connected to said offset end of said upwardly extending lever, the connection between said offset portion of said upwardly extending lever and said rod being forward of pivotal connection between said rod and the foot lever, and 35
 35 means adapted to engage said foot lever to retard the downward movement of said toilet seat and cover.

5. In combination with a toilet having a seat and cover hingedly mounted thereon, means for 40
 40 limiting the upward movement of said seat and cover, a fastening mounted on said toilet seat, a lever extending upwardly pivotally mounted intermediate its length on said fastening one end of

5 said lever extending above said toilet seat when in its closed position, the other end of said lever being offset forwardly, a fastening mounted on said toilet cover forward of said fastening on the toilet seat, a lever having one end pivotally connected to said fastening on the toilet cover and the other end pivotally connected to said upwardly extending lever, a foot lever pivotally mounted at the base of said toilet, a rod pivotally connected to one end of said foot lever and extending upwardly the other end of said rod being pivotally connected to said offset end of said upwardly extending lever, the connection between said offset portion of said upwardly extending lever and said rod being forward of pivotal connection between said rod and the foot lever and means adapted to engage said foot pedal to restore said toilet seat and cover to a closed position. 10
 15

6. In combination with a receptacle having a 20
 20 double cover construction, including an upper cover and a lower cover, provided with hinged mountings at one side of said receptacle, the upper cover to be lifted before the lower cover, and a linkage arrangement to raise said cover 25
 25 successively comprising a short link pivotally mounted at one end on said upper cover, a long link pivotally connected at an intermediate portion of its length to the lower cover, said links being pivotally connected to each other at one 30
 30 end and an actuator connected to the other end of the long link.

7. In combination with a receptacle having a 35
 35 double cover construction, including an upper cover and a lower cover, provided with hinged mountings at one side of said receptacle, the upper cover to be lifted before the lower cover, and a linkage arrangement to raise said cover successively comprising a short link pivotally mounted at one end on said upper cover, a long link pivotally connected at an intermediate portion of its length to the lower cover, said links being pivotally connected to each other at one 40
 40 end and an actuator connected to the other end of the long link, said actuator including a rod and a manual actuating means connected to said 45
 45 rod.

GEORGE HOMPESCH.
